Filed Jan. 25, 1967, Ser. No. 5,554

Term of patent 14 years

(Cl. D45—10)

Fig. 1

Fig. 2

Fig. 3

Fig. 4

FIGURE 1 is a perspective view of a finger ring showing my new design.

FIGURE 2 is a front view thereof.

FIGURE 3 is a side elevational view thereof.

FIGURE 4 is a plan view thereof.

The side not shown is the same as the side shown.

The characteristic features of the design reside in a finger ring in which a bar having a curved jeweled top surface is disposed between two stones of equal size having domed top surfaces substantially flush with the jeweled surface of the bar all as shown.

I claim:

The ornamental design for a finger ring, substantially as shown and described.
